Application October 15, 1937, Serial No. 72,189

Term of patent 3½ years

To all whom it may concern:

Be it known that I, Gustave F. Erhard, a citizen of the United States, residing at Scranton, county of Lackawanna, and State of Pennsylvania, have invented a new, original, and ornamental Design for a Curtain, of which the following is a specification, reference being had to the accompanying drawing, forming part thereof, wherein—

The figure is a plan view of approximately one-half of a curtain showing my new design,

the weave being continued laterally to a selvage edge, in continuation of the design as shown, for the full width of the curtain; and the weave also being continued between the upper and lower portions, shown separated in the drawing, to reproduce additional rows corresponding to element A, for the full length of the curtain.

I claim:

The ornamental design for a curtain substantially as shown and described.

GUSTAVE F. ERHARD.
